UNITED STATES PATENT OFFICE.

ALBERT L. GRANT, OF PHILADELPHIA, PENNSYLVANIA.

DESIGN FOR A SPRING FOR THILL OR SHAFT COUPLINGS.

SPECIFICATION forming part of Design No. 32,961, dated July 17, 1900.

Application filed March 31, 1900. Serial No. 11,024. Term of patent 7 years.

To all whom it may concern:

Be it known that I, ALBERT L. GRANT, a citizen of the United States, and a resident of the city of Philadelphia, in the State of Pennsylvania, have invented and produced a new and original Design for a Spring for Shaft-Couplings, of which the following is a specification, reference being had to the accompanying drawing, forming part thereof.

10 My invention relates to a design for a spring for thill or shaft couplings adapted for use in retaining the thill-iron in position on its supporting-clip.

15 In the accompanying drawing my new design is illustrated by a perspective view.

The leading feature of my design consists of a flat piece of spring metal A, starting at the bottom with a very slight curve, as a, and having its upper portion b of a much greater

curve to form the shape substantially as 20 shown in the drawing. The upper end c of said spring is bent down and under the portion b, this part forming a slight compound curve, as illustrated. The lower end of the portion a has an orifice therein and a projecting footpiece, as d, formed thereon.

Having thus described my invention, what I claim, and desire to secure by Letters Patent, is—

The design for a spring for a thill or shaft 30 coupling, substantially as herein shown and described.

In witness whereof I have hereunto set my hand this 27th day of March, A. D. 1900.

ALBERT L. GRANT.
